UNITED STATES PATENT OFFICE.

GEORGE WEBBER BLANCHARD, OF WATERVILLE, MAINE, ASSIGNOR OF ONE-HALF TO SOPHIA G. WEBBER, OF SAME PLACE.

ELECTRIC-CAR-STOPPING DEVICE.

SPECIFICATION forming part of Letters Patent No. 449,843, dated April 7, 1891.

Application filed October 16, 1890. Serial No. 368,343. (No model.)

To all whom it may concern:

Be it known that I, GEORGE WEBBER BLANCHARD, a citizen of the United States, residing at Waterville, in the county of Kennebec and State of Maine, have invented certain new and useful Improvements in Electric-Car-Stopping Devices; and I do hereby declare the following to be a full, clear, and exact description of the invention, such as will enable others skilled in the art to which it appertains to make and use the same.

The chief objects of this invention are to provide a positive gear-locking device for electric cars, which will become operative to stop the car if the latter, on failure of the current, begins to run backward downhill, and to arrange for controlling the braking devices and also the impelling-motor of the car by a single circuit-closer and indicator, which may be located on the platform and easily manipulated. To attain these objects I make use of the devices hereinafter particularly set forth and claimed.

In the accompanying drawing, the figure 25 represents my improved gear-locking devices partly in vertical section and side elevation partly in diagram.

A represents the floor of the car.

In a bushing *b*, fastened to the railing of the car-platform, there is journaled the horizontal shaft *C* of a hand-wheel *C'*, said shaft also bearing an indicator-finger *C²*. The feed-wire *F* on entering the car passes first to a solenoid *U* and thence to a switch-bar *Y*, having a handle *Y'*. From this point the feed-wire divides, or, speaking more exactly, there are two supplemental wires *F' F²*. The former extends directly from a contact *f'* on a switch-board *f* (attached to the railing of the car-platform) to said shaft *C²* or an attachment thereof. The other wire *F²* extends from another contact-post *f²*, on said switch-board *f* to a small magnet *r*, and thence to said shaft *C²* or any attachment thereof.

When the switch-bar *Y* is on contact *f'*, the circuit is thus through solenoid *U* only, and when said bar *Y* is on contact *f²* the circuit is through the small magnet *r* and through solenoid *U* also. A magnetic bar *V* is movable endwise up and down in the hollow core *u* of solenoid *U*. It carries at its lower end

a block *V'*, provided with cog-teeth *v'*, arranged to engage the motor-gears *V² V³*, and thus lock the car whenever said bar and block are left free to descend. While the solenoid 55 *U* is in circuit the said block is held up out of engagement and the gears *V² V³* are free to turn, so that the car may run; but a failure of electric current through said solenoid from any cause arising will end the attractive power of said solenoid, and the bar and block will be no longer prevented thereby from falling and locking, as stated; but this would be very inconvenient on level ground, and in ordinary circumstances I therefore 65 provide the said bar on one side with a shoulder or enlargement *v²* and arrange a pivoted stop *v³* to bear obliquely upward against it, holding said bar from falling. This stop is attached to a hanger or frame *v⁴*, which is 70 made fast to the under side of the floor of the car, and also supports the said small magnet *r*. This magnet is in proximity to said stop and arranged so that when energized it will attract the upper part of said stop, which is metallic, away from said shoulder, the stop turning as a pivoted armature against said magnet. When this small temporary magnet *r* is demagnetized, the pivoted stop drops again 75 into position for holding up said bar and 80 block. To allow this the magnet and stop are inclined, as shown.

The operation of this locking device is as follows: When running along level ground, the circuit is through contact *f'* and solenoid *U*, the block is out of gear, and the pivoted stop holds it so. If then the circuit is accidentally broken or the current fails, the gearing will not be locked and the car will run for a short distance by its own momentum, stopping gradually with no jar, or not stopping at all if the defect be remedied in time; but in ascending a hill, or just before doing so, the switch-bar *Y* is shifted to contact *f²*, as shown, and the circuit is then 90 through both the solenoid *U* and the small magnet *r*. The former still holds the block out of engagement with the gears, but the latter draws away the stop, as described, so that there is nothing else to support said block. 95 If then the current fails, the bar and block will drop at once before said pivoted stop can 100

check them and the gearing will be locked, preventing the car from running backward downhill.

Having thus fully described my invention, what I claim as new, and desire to secure by Letters Patent, is—

1. A locking device for the gears of an electric motor, in combination with a solenoid or magnet and electrical connections for holding said locking device normally out of engagement, as set forth.

2. In combination with the motor-gears of an electrically-operated vehicle, a block provided with cog-teeth and arranged to automatically engage with said gears, a solenoid or magnet which normally holds said block out of such engagement, and the necessary electrical connections and circuit-closing devices, substantially as set forth.

3. A locking device for the motor-gears of an electric car, in combination with a movable stop for holding it out of engagement, a

magnet for withdrawing said stop, and the electrical conductors and circuit-closing devices, substantially as set forth.

4. A movable block provided with cog-teeth and a metallic bar to which it is attached, in combination with the motor-gears of an electric car, said gears being arranged to be locked by said block when it descends, a solenoid and movable stop independently holding up said bar and block, a magnet arranged to attract and withdraw said stop, electric conductors making a circuit through said solenoid only and another circuit through said solenoid and said magnet, and a switch-bar controlling both of said circuits, substantially as set forth.

In testimony whereof I affix my signature in presence of two witnesses.

GEORGE WEBBER BLANCHARD.
